UNITED STATES PATENT OFFICE.

HUGO F. GUDDE, OF CLEVELAND, OHIO.

MUSIC-TURNER.

1,073,851.

Specification of Letters Patent. Patented Sept. 23, 1913.

Application filed October 10, 1912. Serial No. 724,927.

To all whom it may concern:

Be it known that I, HUGO F. GUDDE, a citizen of the United States, residing at Cleveland, in the county of Cuyahoga and State of Ohio, have invented a certain new and useful Improvement in Music-Turners, of which the following is a full, clear, and exact description, reference being had to the accompanying drawings.

10 This invention relates to music turners, or devices whereby the leaves of books may be rapidly and automatically turned by mechanical means when the operative parts thereof are released by the suitable actuation 15 of releasing mechanism. These devices, as is well known, are more favored for use in turning music than for any other purpose, partly owing to the rapidity of their operation, and partly to the fact that a performer's hands are so fully occupied with 20 the rendition of the selection as to render it inconvenient or impossible for him to turn the music by hand. When employed for a keyboard instrument such as a piano or organ, the device is sometimes made to be released by a hand-pressed trigger and sometimes by a foot operated pedal, the idea of the former arrangement being that although 25 the performer might not have sufficient time 30 to enable him to turn the sheet by hand he would still have sufficient time to touch a trigger, in case such trigger were sufficiently conveniently located. Many devices of this type have already been proposed but 35 the same have generally been inefficient either because of their mechanical complexity, their operative unreliability, the difficulty of setting them in the first place, or the difficulty of resetting them for a succeeding 40 operation.

Among the objects of the present invention are the provision of a device of great simplicity, durability, reliability and convenience of manipulation; the provision of a 45 device which can be easily set and easily reset; the provision of a device of this character wherein the different turning arms shall at all times lie close to the plane of the paper, and shall at all times preserve an echelon or 50 stepped arrangement so that the different arms may never conflict with each other; the provision of a device wherein upon the movement of each arm from one side to the other the remaining arms shall move sufficiently to make room for it; while other ob-

jects and advantages of the invention will become apparent as the description proceeds.

In brief, my invention may be defined as consisting of the combinations of parts recited in the claims hereto annexed and illustrated in the drawings accompanying and forming part of this application, wherein—

Figure 1 is a perspective view of a music rack equipped with my improved device, 60 the same being shown in connection with a piece of music whose leaves are to be turned. Fig. 2 is a vertical transverse cross-sectional view of the same parts showing the turner in side elevation; Fig. 3 is a plan view of 65 the turner alone, a portion of the top plate being broken away so as to show the interior construction; Figs. 4 and 5 are transverse cross-sectional views taken upon similarly numbered lines of Fig. 3; Fig. 6 is a 70 detail cross sectional view taken on the line 6—6 of Fig. 5; and Fig. 7 is a horizontal cross sectional view taken on the line 7—7 of Fig. 4 and looking upwardly.

In these drawings I have shown my improved mechanism as accompanying a peculiar form of music stand, although it is to be understood that the turning mechanism may, and frequently will, be sold separately from the stand with the intent that 80 it be applied to existing stands of whatever type. I have illustrated it thus in connection with a stand so that its mode of operation might be clear, but without intent to limit myself to the particular combination 85 shown. This particular stand comprises a flat, book supporting member 1, of metal or other suitable material made in any desired design and provided at each end with a bracket 2 whereby it may be secured to a 90 piano, organ, table, or other support. A clip 3 of wire or other resilient material is 95 preferably carried by the supporting member so as to overlie the face thereof and receive the back of the music book placed thereon and define the position of the back or fold thereof. At the top of the supporting member 1 is a bracket 4 and to this bracket is attached my improved turning device; the construction whereof will now 100 be described.

This device comprises a rectangular metallic body 5 having in its upper side a parallel walled recess 6, here illustrated as running from end to end of the body, and 110

mounted in this recess are a plurality of parallel spacing-plates 7—7 defining a plurality of parallel-walled guide-ways 8 whose number will depend upon the number 5 of arms which the device is designed to possess. These spacing plates may be secured in place in any convenient manner as by inserting their lower edges in narrow grooves 9 formed in the body 5 at the bottom of the recess 6. Slidably mounted in these guideways are elongated metallic blocks 10^a—10^b—10^c—10^d and 10^e (up to the 10 number of the guide ways provided) in which are journaled rotatable shafts 11^a, 11^b, 11^c, etc., respectively. The lower portion 15 of each of the blocks is recessed as at 12 for the reception of a pinion 13 carried by the corresponding shaft as clearly shown in Figs. 4 and 7. The portion of the block 20 10^b adjacent to the block 10^a is formed with a toothed rack 14^b meshing with the pinion 13 carried by the shaft 11^a, the recess 12 being suitably elongated as illustrated at 15 so as to permit relative movement of the 25 blocks past each other. Likewise each of the remaining blocks 10^c, 10^d, 10^e, etc., is provided with a similar rack meshing with the pinion carried by the preceding block. The pinion carried by the last block (in 30 this case block 10^e) meshes with a stationary rack 14^e fixedly attached to the block 5 at the side of the guideway in which this block reciprocates. The spacing-plates 7 are 35 formed with longitudinal slots 16 as shown in Fig. 7 for the reception of the various racks. Each of the blocks 10^a, 10^b, 10^c, etc., with the exception of the last block is also 40 preferably provided with a laterally projecting pin or stud 17 projecting through the slot 16 into an elongated recess 18 in the face of the adjacent block so as to limit the movement of each block relative to its neighbor sufficiently to prevent disengagement 45 between the various racks and pinions. Moreover the length of the recess 18 and the size of the pinion 13 is such as to impart 50 to each of the shafts 11^a, 11^b, 11^c, etc., a rotation of substantially 180 degrees upon the movement of the block from one extreme of its motion to the opposite extreme. The longitudinal movement of the 55 last block of the series is here shown as limited by means of a fixed block 19 mounted in the end of the corresponding guideway, although other means could obviously be employed.

For the purpose of controlling the movement of the various blocks and their corresponding shafts, the following arrangement 60 may be employed. The bottom portion of the body 5 is provided at a point in the rear of the middle thereof with a plurality of narrow transverse slots 20—20 traversing the guideways 8—8 and preferably at substantially right angles thereto. A pin 21

parallel to the guideways 8—8 traverses the slots 20—20 at one end thereof, and upon this pin are pivoted a plurality of triggers 22^a, 22^b, 22^c, etc., one for each slot. These triggers are formed at their free ends with 70 upturned rounded fingers 23^a, 23^b, etc., adapted to be introduced into the guideways 8—8 in the rear of blocks 10^a, 10^b, 10^c, etc. These triggers are yieldingly held in elevated position by means of leaf springs 24 75 pressing against the lower or rear sides thereof and conveniently carried by a removable plate 25 secured in a recess in the bottom of the body 5. The finger 23^a being that which lies nearest the forward ends of 80 the body 5 and the blocks 10^a, 10^b, 10^c, etc., being of substantially equal length it will be seen that the shafts 11^a, 11^b, 11^c, etc., will be located in echelon formation when the device is set in readiness for operation. Between the forward end of each block and the forward end of its guideway a helical expansion spring 26 is compressed, the forward ends of all the springs preferably being abutted against a plate 27 inset in the 85 end wall of the body 5. The top and sides of the body 5 are preferably covered and inclosed by a metal casing member 28 whereby all of the working parts are inclosed and covered, the top of this casing being formed 90 with a plurality of parallel slots 29^a, 29^b, etc., through which project the shafts 11^a, 11^b, etc., respectively.

Rigidly secured to the shafts 11^a, 11^b, 11^c, etc., are radial arms 31^a, 31^b, and 31^c, etc., respectively, and to the outer ends of these arms are pivoted depending fingers 32^a, 32^b, etc., adapted to be interposed between the various sheets which are to be turned, as clearly illustrated in Fig. 1. The arrangement of 105 the shafts 11^a, 11^b, etc., in echelon formation permits these arms to lie closely adjacent to and parallel with each other and without interference.

Rotatably mounted in a socket 35 formed 110 in the body 5 parallel to and forward of the pin 21 is a cylindrical drum 36 which traverses the top of all the triggers 22^a, 22^b, etc., and has upon its surface a plurality of circumferential grooves 37^a, 37^b, etc., 115 which register with the triggers 22^a, 22^b, etc., respectively. These grooves are each intersected at least at one point by sloping-sided obstructions 38^a, 38^b, etc., the obstructions in successive grooves being arranged 120 otherwise than in direct alinement and progressing uniformly about the circumference of the drum. Likewise each of the triggers 22^a, 22^b, etc., is provided with an inclined projection 39 projecting into the corresponding groove.

The outer end of the drum 36 is formed with ratchet teeth as illustrated at 40, while in the outer end of the recess 35 is mounted 125 a rock shaft 41 having a spring pressed 130

pawl 42 engaging said ratchet teeth, said rock shaft also having secured to its outer end a lever arm 43 whereby it may be operated. Suitably pivoted to the brackets 2-2 are forwardly extending levers 44-44 connected by a cross bar 45 to which is attached a reciprocating rod 46, the upper end of which is articulated to the lever 43 as shown in Fig. 2. A coil spring 47 is employed to maintain this rod in raised position, while the forward ends of the arms 44-44 may be connected by means of a finger-bar 48 by which the arms together with the reciprocating rod 46 may be depressed at will.

The operation of the device is as follows: The various parts being set as illustrated in the drawings, with the fingers 32^a, 32^b, etc., interposed between successive sheets of music, if the bar 48 be depressed, the rock shaft 41 and drum 35 will be rotated together so as to cause the depression of the trigger 22^a and the release of the block 10^a. This block, under the influence of the spring 26, now moves forwardly relatively to the block 10^b by the amount permitted by the pin 17 and slot 18, the shaft 11^a being meanwhile rotated by the action of the rack 14^a, and the arm 31^a swung through an angle of 180° carrying with it the music sheet. This action, therefore, not only turns the arm 31^a through a semicircle, but moves its pivot rearwardly to a distance as much in the rear of the pivot of the succeeding arm as it originally was in front of such pivot. If now the finger bar 48 be again depressed, the trigger 22^b will be forced downwardly, releasing the block 10^b which likewise moves rearwardly past the block 10^a, meanwhile rotating its shaft 11^b, and swinging the arm 31^b through a half revolution. This action is then arrested by the pin and slot engagement with the following block, at which time the shaft 11^b will have moved past 11^a to an extent equal to its original advance forward of that shaft. The block 10^a will accompany the block 10^b in its rearward movement but without any movement of the shaft 11^a. Similarly the remaining arms can be actuated successively, the actuation of each arm being caused by the movement of its block relatively to the succeeding block and carrying with it the block or blocks preceding it until the whole number of arms has been actuated, whereupon they will be found to possess the same echelon arrangement but in reverse order. Meanwhile all of the fingers 23^a, 23^b, etc., of the various triggers will be rubbing against the bottoms of the different blocks but without obstructing their movement since the same are smooth and uninterrupted at their rearward ends.

In order to reset the device for a succeeding operation it is necessary merely to rotate the arm 31^a back to its original position,

carrying the remaining arms before it, the interaction of each pinion with its corresponding rack serving to force its corresponding block forward in its guideway against the action of its spring 26 until the rear ends of all of the blocks are moved past their corresponding triggers, whereupon the triggers are elevated by their springs so as to retain the same until released for a succeeding operation. Of course the different arms can be set back separately without damage to the apparatus although such care is not necessary.

In the present embodiment I have illustrated each of the grooves 37^a, 37^b, etc., in the drum 36 as formed with two diametrically opposite obstructions 38^a, 38^b, etc., respectively, the obstructions in successive grooves being displaced forwardly through an angle of one-fifth of 180° or 36°. Accordingly, it will be seen that after five reciprocations of the rod 46 whereby the five triggers 22^a, 22^b, etc., have successively been released so as to permit the actuation of the arms 31^a, etc., the drum 36 will have been rotated through 180°; wherefore, upon the resetting of the blocks 10^a, 10^b, etc., the opposite obstruction 38^a will be in position to actuate the trigger 22^a so as to free the block 10^a upon the following reciprocation of the rod 46. It will be understood, however, that this is merely a matter of design and can be varied widely within the scope of my inventive idea. In fact this feature will depend largely upon the number of arms 31 employed, since if ten or more were used it would probably be impossible to crowd ten or more obstructions into the half of the groove without making the drum unduly large, while if so small a number as three were used it might be necessary to subdivide the circumference of the drum still more finely in order to reduce the angle turned between actuations of successive levers. Also, while I have illustrated and particularly described a construction in which the shafts 11 are arranged in echelon formation irrespective of the position of the arms 31, it will be understood that similar results would be obtained in case the shafts were in straight line formation at one position of the arms 31, the echelon formation being acquired when the arms are turned to opposite position. Although for purposes of symmetry I prefer the arrangement illustrated, I consider this modification the substantial equivalent thereof and desire that my claims be read with this in view.

Furthermore it will be understood that I esteem my invention to reside entirely within the turning device proper, meaning thereby the parts numbered 5 to 43 inclusive, inasmuch as it is obvious that the same can be employed with music stands of a great many different types and that the releasing mecha-

nism may take a great many forms other than that herein shown without departing from my inventive idea.

Finally it will be understood that while I have described in detail and particularly pointed out that form of construction which appears most desirable to me at the present time, I do not propose to be limited to such details or features of construction except as 10 the same may be positively recited in the claims hereto annexed or rendered necessary by the prior state of the art.

Having thus described my invention, what I claim is:

- 15 1. In a device of the character described, in combination a plurality of arms pivoted at one end, the pivotal points of said arms being adjacent to each other and arranged in echelon formation whereby said arms, 20 when turned in the same direction, may lie closely adjacent to and parallel with each other, means for rotating said arms successively about their pivots beginning with the forward arm of the series, the angle of 25 movement of each arm being substantially one hundred and eighty degrees, and for simultaneously shifting the pivotal points of such arms past the pivotal points of the succeeding arms, whereby said arms when in 30 reverse position will lie closely adjacent to and parallel with each other with their pivotal points still in echelon formation, but arranged oppositely to their arrangement at the beginning of the operation.
- 35 2. In a device of the character described, in combination, a plurality of arms pivoted at one end, the pivotal points of said arms being adjacent to each other and said arms being so formed relatively to their pivots as 40 to lie closely adjacent to and parallel with each other when turned in the same direction, means for rotating said arms about their pivots beginning with the forward arm of the series, the angle of movement of each 45 arm being substantially one hundred and eighty degrees, and for simultaneously shifting the pivotal point of the arms which have already been moved past the pivotal points of the arms yet to be moved, whereby said 50 arms when in reverse position will lie closely adjacent to and parallel with each other.
- 55 3. In a device of the character described, the combination with a support for an open book, of a plurality of arms pivoted upon 60 axes substantially parallel with the face of said support, such pivotal axes being arranged in echelon formation and respectively increasing in distance from the plane of said support whereby said arms when 65 turned in the same direction may lie closely adjacent to each other and parallel both to each other and to the plane of said support, fingers carried by said arms adapted to engage the leaves of the book or like article carried by said support, means for rotat-

ing said arms successively about their pivots through an angle of substantially one hundred and eighty degrees and for simultaneously shifting the pivotal point of such arm toward the rear of the pivotal point of 70 the succeeding arm whereby the echelon arrangement of the pivots will be reversed simultaneously with the reversal of the position of the arms.

4. In a device of the character described, 75 the combination with a support for an open book, of a plurality of arms pivoted upon axes substantially parallel with the face of said support, such pivotal axes being arranged in echelon formation so that when 80 said arms are turned toward the right they will lie closely adjacent to and parallel with each other and also substantially parallel to the face of said support with the pivot of the foremost arm located at the left of the 85 series and farthest removed from the plane of said support, fingers carried by said arms adapted to engage the leaves of the book or like article carried by said support, means for rotating said arms successively about 90 their pivot through an angle of substantially one hundred and eighty degrees, beginning with the nearest of said arms and for simultaneously shifting the pivotal point of such arm and of all previously moved arms toward the rear of the pivotal points of the 95 arms remaining to be moved whereby the echelon arrangement of the pivots will be reversed simultaneously with the reversal of the position of the arms.

5. In a device of the character described, the combination, with a plurality of relatively movable members arranged side by side, of rotatable shafts journaled in and projecting beyond said members and having 105 their axes substantially perpendicular to the direction of movement of said members, radial arms carried by said shafts and arranged when turned to a position substantially perpendicular to the direction of 110 movement of said members to lie closely adjacent to and parallel with each other, means for successively moving each member beginning with the end member of the series past the succeeding members and means for 115 simultaneously rotating the shaft carried by such member so as to reverse the position of the arm secured thereto.

6. In a device of the character described, the combination, with a plurality of relatively movable members arranged side by side, of rotatable shafts journaled in and projecting beyond said members and having 120 their axes substantially perpendicular to the direction of movement of such members, operative connections between each of said shafts and the succeeding member for causing a rotation of said shaft to accompany 125 every movement of that member relatively thereto, means for restricting such relative 130

movement to an amount which shall cause substantially a half rotation of said shaft, radial arms carried by said shafts and arranged when turned to a position substantially perpendicular to the direction of movement of said members to lie closely adjacent to and parallel with each other, and means for successively moving each member beginning with the end member of the series 10 past the succeeding members and thereby rotating the shaft carried by such member so as to reverse the position of the arm secured thereto.

7. In a device of the character described, 15 the combination, with a plurality of members arranged side by side and movable relatively to each other in a longitudinal direction, of rotatable shafts journaled in and projecting beyond said members and having 20 their axes substantially perpendicular to the direction of movement of said members, radial arms carried by said shafts and arranged when turned into a position substantially perpendicular to the direction of 25 movement of said members to lie closely adjacent to and parallel with each other, connections between each member and the shaft carried by the preceding member whereby upon the longitudinal movement of the preceding 30 member relatively to such succeeding member, the shaft carried by said preceding member will be rotated through an angle of substantially one hundred and eighty degrees, means tending to shift all of said members in the same direction, and means 35 for releasing said members successively beginning with the first member of the series so as to permit them to advance past the remaining members of the series.

40 8. In a device of the character described, the combination, with a plurality of relatively movable members arranged side by side, of rotatable shafts journaled in and projecting beyond said members and having 45 their axes substantially perpendicular to the direction of movement of said members, radial arms carried by said shafts and arranged when turned to a position substantially perpendicular to the direction of movement 50 of said members to lie closely adjacent to and parallel with each other, connections between each member and the shaft carried by the preceding member whereby upon the movement of each of such preceding members 55 relatively to its succeeding member, the shaft carried by said preceding member will be rotated through an angle of substantially one hundred and eighty degrees, interengaging means carried by the neighboring 60 members of the series whereby their movement relative to each other is limited to the amount necessary to impart to each shaft a rotation of substantially one hundred and eighty degrees, and means for releasing 65 said members successively beginning

with the first member of the series so as to permit each member in turn in company with all the preceding members to advance past the remaining members of the series, each of the members of said series after its original release being restrained in its forward movement only by said interengaging means. 70

9. In a device of the character described, the combination, with a plurality of relatively movable members arranged side by side, of a shaft journaled in each of said members and projecting beyond the same, the axis of each shaft being substantially perpendicular to the direction of movement 75 of its member, a pinion carried by each of said shafts, a rack carried by each of said members excepting the first member of the series and meshing with the pinion carried by the shaft of the preceding member, 80 a fixed rack engaging the pinion of the last member of the series, means tending to shift all of said members in the same direction, means whereby said members may be released successively beginning with the first 85 member of the series to move under the influence of such means relatively to the succeeding members, means carried by each of said members and engaging the neighboring member whereby the amount of movement 90 of each member relative to its neighbor is limited to the amount required to impart to its shaft a half-rotation, and radial arms carried by said shafts and adapted to lie closely adjacent to and parallel with each 95 other, said arms prior to the release of any of said members lying substantially perpendicular to the direction of movement of said members. 100

10. In a device of the character described, 105 the combination, with a supporting body having parallel guideways, of a member slidably mounted in each guideway and movable relatively to the neighboring members, a shaft journaled in each of said members and projecting beyond the same, the axis of said shaft being substantially perpendicular to the direction of movement of said member, a pinion carried by each of said shafts, a rack carried by each of said 110 members excepting the first member of the series and meshing with the pinion carried by the shaft of the preceding member, a rack carried by said supporting body and engaging the pinion of the last member of 115 the series, means limiting the relative movement of neighboring members to the amount necessary to impart to the shaft of the preceding member of the pair a half-rotation, 120 means for advancing said members successively beginning with the first member of the series, means for maintaining in fixed position the members succeeding the member being advanced, means for advancing 125 the preceding members of the series 130

uniformly with the member being advanced, and radial arms carried by said shafts and adapted to lie closely adjacent and parallel to each other, said arms prior to the release of any of said members lying substantially perpendicular to the direction of said members.

11. In a device of the character described, the combination, with a supporting body, of a plurality of longitudinally movable members carried thereby, a rotatable shaft carried by each of said members and journaled upon an axis substantially perpendicular to the direction of movement thereof, radial arms carried by said shafts, means for maintaining said members in such relative position that said arms, when turned in one direction, lie closely adjacent to and parallel with each other, means for rotating said shafts successively so as to swing said arms respectively through substantially a half circle, and means for simultaneously shifting said blocks relatively to each other so as to move the shafts of the previously moved arms into the rear of the shafts of the arms remaining to be moved so as to permit said arms to lie closely adjacent to and parallel with each other when in reversed position.

12. In a device of the character described, the combination, with a book support of a body having guideways substantially normal to the plane thereof, a longitudinally movable member in each guideway, a rotatable shaft carried by each of said members and journaled upon an axis substantially parallel to the plane of said book support, radial arms carried by said shafts, means for maintaining said shafts in such relative position that said arms, when turned in one direction, lie closely adjacent to and parallel with each other, fingers carried by said shafts and adapted to engage the leaves of a book on said support, means for releasably retaining said members in the portions of their respective guideways furthest removed from the plane of said book support, said arms at that time being turned to the right and the first or outside arm being connected to the left hand member, the next arm being that connected to the next member at the right, etc., means for successively shifting along their guideways toward the plane of said book support the members beginning with the left hand member so as to shift toward such plane the shafts carried thereby, and means operative simultaneously with the shifting of each member for rotating in a clockwise direction the shaft carried thereby so as to reverse the position of its arm.

13. In a device of the character described, the combination, with a supporting body, of a plurality of separately movable blocks carried thereby, a rotatable shaft carried by each of said blocks, the axis of each shaft

being substantially perpendicular to the direction of movement of its block, means tending to move all of said blocks in the same direction, detent means for releasably holding said blocks against such movement, mechanism for releasing said detent means in succession so as to free said blocks successively means for rotating each of said shafts through substantially an angle of one hundred and eighty degrees simultaneously with the longitudinal movement of its supporting block, and radial arms carried by said shaft and adapted to lie closely parallel to and adjacent to each other both in direct and reverse position.

14. In a device of the character described, the combination, with a plurality of separately movable members, of a rotatable shaft carried by each of said members, the axis of each shaft being substantially perpendicular to the direction of movement of its member, means tending to move all of said members in the same direction, a plurality of spring pressed triggers adapted to be inserted into the path of movement of said members whereby the same may be held against movement, mechanism for withdrawing said triggers in rotation so as to free said members successively, means for rotating each of said shafts through substantially an angle of one hundred and eighty degrees simultaneously with the longitudinal movement of its supporting member relative to the neighboring member, and radial arms carried by said shafts and adapted to lie closely parallel to and adjacent to each other both in direct and reversed position.

15. In a device of the character described, the combination, with a supporting body, of a plurality of slidable members carried thereby, said members being separately movable along substantially parallel paths and each of said members having a shoulder and a smooth portion adjacent to said shoulder, a rotatable shaft carried by each of said members, the axis of each shaft being substantially perpendicular to the direction of movement of each member, means tending to move all of said members in the same direction, a plurality of spring-pressed triggers carried by said supporting body, one of said triggers being adapted to engage the shoulder of each of said members whereby the same may be held against movement, mechanism for withdrawing said triggers in rotation so as to free said members successively, means for thereafter releasing said triggers so as to permit them to engage the portions of their respective members adjacent to the shoulders thereof, whereby said triggers may reengage said shoulders in obstructing position upon the resetting of said members, means for imparting to each of said shafts a half rota-

tion simultaneously with the longitudinal movement of its member relative to the neighboring member, and radial arms carried by said shafts and adapted to lie closely parallel with and adjacent to each other both in direct and reversed position.

16. In a device of the character described, in combination, a plurality of shouldered members, said members being separately movable along substantially parallel paths, a rotatable shaft carried by each of said members, the axis of each shaft being substantially perpendicular to the direction of movement of each member, means tending to move all of said members in the same direction, spring - pressed detent mechanism adapted to engage the shoulders of said members whereby the same may be held against movement, the portion of each member adjacent to the shoulder thereof being smooth and uninterrupted, mechanism for disengaging said detent mechanism from said shoulders in succession beginning with the first member of the series so as to free said members successively, said mechanism being arranged to release said detent mechanism immediately after the movement of the shoulder there past and permit it to engage the portion of its respective member adjacent to such shoulder whereby it may reengage said shoulder in obstructing position upon the resetting of said member, means for imparting to each of said shafts

a half rotation simultaneously with the longitudinal movement of its member relative to the neighboring member, and radial arms carried by said shaft and adapted to lie closely parallel with and adjacent to each other both in direct and reverse position.

17. In a device of the character described, the combination, with a supporting body, of a plurality of separately movable blocks carried thereby, a rotatable shaft carried by each of said blocks, the axis of each shaft being substantially perpendicular to the direction of movement of the blocks, a radial arm carried by each of said shafts, means tending to move all of said blocks in the same direction, means for imparting to each of said shafts a half rotation simultaneously with the longitudinal movement of its block relative to the neighboring block, a trigger operatively associated with each of said blocks whereby the same may be held against movement, a reciprocable member, and connections between said reciprocable member and each of said triggers whereby upon each successive reciprocation thereof, successive triggers beginning with the first trigger of the series will be released.

In testimony whereof, I hereunto affix my signature in the presence of two witnesses.

HUGO F. GUDDE.
